[57] CLAIM

The ornamental design for a ported filter for processing fluids, as shown and described.

DESCRIPTION

FIG. 1 is a perspective view of the ported filter for processing fluids of the present invention;

FIG. 2 is a top view of the ported filter for processing fluids shown in FIG. 1;

FIG. 3 is a front view of the ported filter for processing fluids shown in FIG. 1;

FIG. 4 is a left side view of the ported filter for processing fluids shown in FIG. 1;

FIG. 5 is a right side view of the ported filter for processing fluids shown in FIG. 1;

FIG. 6 is a bottom view of the ported filter for processing fluids shown in FIG. 1; and,

FIG. 7 is a back view of the ported filter for processing fluids shown in FIG. 1.
